CENTRIFUGAL CASTING APPARATUS
Belton Y. Cooper, Mountain Brook, and Clifford M. Luna,
Birmingham, Ala., assignors to United States Pipe and
Foundry Company, Birmingham, Ala., a corporation of
New Jersey

Filed Feb. 19, 1962, Ser. No. 173,995

9 Claims. (Cl. 22—65)

This invention relates to centrifugal casting apparatus and process, and more specifically it relates to improvements in apparatus and processes for carrying out a process such as is disclosed in United States Letters Patent No. 2,853,755.

In a process of the type to which the invention relates, pipe is cast in a metal mold mounted on a carriage which is movable along its longitudinal axis. Molten metal is poured into the spinning mold through an opening in the center of the bell core by means of a horngate. As soon as the metal has set up sufficiently, the pipe is extracted by moving the mold longitudinally over a push-out lance which pushes against the end of the pipe. The mold is then returned to casting position, and a coating is simultaneously applied by means of a spraying device mounted in the push-out lance. A new bell core which has been placed on a support around the horngate spout is automatically seated in the mold as the horngate spout enters the returning mold.

In United States Letters Patent No. 3,004,314, there is disclosed apparatus and process which permit the horngate to be withdrawn as soon as molten metal is poured into the mold. This provides increased time for servicing of the horngate since previously the horngate could not be withdrawn until the metal had solidified. There is, however, no decrease in the work load on the operating crew.

In order to complete a casting cycle, according to the procedures disclosed and claimed in Patent No. 2,853,755 and Patent No. 3,004,314 there are many duties which must be performed by the operating crew, for example, the horngate must be serviced, the core back-up plate must be transferred from the mold to the core setter, a new core must be placed on the core setter, the machine ladle must be filled, the metal must be prepared for casting, and the casting machine operation must be closely observed and controlled. If higher casting rates, which are possible due to the use of a two stroke cycle as contrasted to previous methods which use a four stroke cycle, are to be attained, it is apparent that these duties must be rapidly and efficiently carried out in a very limited time and if they are not performed in the time which elapses during solidification of the metal, extracting of the pipe and coating of the mold then the machine cannot be operated at its maximum rate. In order to obtain a high rate of production, it is necessary to maintain an operating crew of two or more men, but even then it is not always possible to prevent delays due to human inefficiencies and deficiencies.

To obtain maximum efficiency and output, the operating crew must be kept to a minimum and all unnecessary delays prevented. To accomplish this, the duties which are to be performed manually must be simplified and reduced to a minimum so that they can readily be performed in the short time allotted by the rapid casting rate which it is desirable to attain. Accordingly, this invention has for its object the provision of methods and apparatus pointed to this end.

More specifically, this invention has for its object the provision of an apparatus capable of automatically picking up a core backing plate from its position of use at the bell end of the mold and transferring it to a core setting mechanism mounted on a horngate spout.

2

A further object is the provision of a method of operating whereby a core back-up plate may be mechanically transferred from its position of use in the mold to a core setting mechanism mounted on the horngate.

5 A still further object is to provide apparatus and a method of operation which will permit either rapid manual or preferably a simple mechanical placement of the bell core onto the core setter surrounding the horngate spout.

10 This invention has other objects that will be apparent from a consideration of the following description and the specific embodiment shown in the accompanying drawings. Such embodiment will now be described in detail to illustrate the general principles of the invention, but 15 it is to be understood that such detailed description is not to be taken in a limiting sense. The scope of the invention is defined by the claims appended hereto. In the drawings:

FIGURE 1 is a top view, with broken away portions, 20 of the bell end of a casting machine incorporating the apparatus of this invention, and it illustrates conditions immediately after molten metal has been poured into the mold.

25 FIGURES 4 through 7 are diagrammatic drawings illustrating the various steps in the novel process of the present invention.

FIGURE 2 is a side view and FIGURE 3 is a front view of the core ring transfer arm which is part of the combination making up the apparatus of this invention.

30 Referring now to FIGURE 1, only the bell portion of the casting machine is shown since the structure of casting machines is well known to those skilled in the art, and it is obvious that the present invention may be adapted for use with casting machines of varied designs. 35 Metal mold 1 is rotatably mounted, by means not shown, in water box 2 and is fitted with mold flange 3. The mold flange is provided with three or more centrifugal latches 4 evenly spaced around its circumference. One end of each centrifugal latch terminates in a hook 7 while the opposite end is provided with weights 8. Each latch 4 is positioned to permit hook 7 to hook over the lip of the bell flange 3, as shown, when the mold is spinning. In order to keep the hook ends 7 clear of the bell cavity except during rotation of the mold, the latches are provided with spring bias means, not shown, which hold the latches in the positions shown in FIG. 4 until the bias is overcome by centrifugal force.

Opposite the end of the water box 2 horngate 10 is mounted on shifter plate 11 which is movable along track 50 14 in the direction of the longitudinal axis of the mold by means of hydraulic cylinder 12. A core setting means 15 which encircles spout 13 of horngate 10 rotatably holds core 16 and core back-up plate 17 about the horngate spout. The portion of the apparatus described to this 55 point is similar to the apparatus disclosed in said United States Letters Patent 3,004,314 which more particularly describes the operation and structure of the centrifugal core latches and the core setting means.

The horngate shifter plate 11, with horngate 10, is 60 mounted on a secondary shifter plate 18 which may be shifted transversely to the longitudinal axis of the mold 1 along tracks 19 by suitable means such as a hydraulic cylinder 42. In addition to the horngate there are mounted on the secondary shifter plate 18 a core ring pick-up means 20 and a core ring transfer mechanism 21. The longitudinal axis of both the core ring pick-up means 20 and core ring shifter mechanism 21 are arranged parallel to the longitudinal axis of the mold 1 and the horngate spout 13.

70 The core ring pick-up means 20 comprises a magnet 22, preferably an electromagnet which may be energized and

deenergized as desired, with a pole face 23 designed to engage and firmly hold core back-up plate 17. The magnet 22 is mounted at the end of shaft 25 which is rotatably mounted by means of bearing blocks 26. A coil spring shock absorber 27 is provided to permit the magnet 22 to move with respect to shaft 25 for reasons which will be pointed out later. Alternately, the pick-up magnet 22 may be mounted on the piston rod of a pneumatic cylinder.

The core ring transfer mechanism comprises an arm 30 mounted on the shaft of a reversible rotor 31, for example, a fluid driven rotor such as a "ROTAC". This arm is shown in more detail in FIGURES 2 and 3. The swing of the arm in either direction is controlled by block 33 encountering adjustable stops 32. The transfer head 34 is adjustably mounted in transfer arm 31 by means of bolts 35 to permit adjustment of the overall length of the assembly. The transfer head terminates in two fingers 36 and 37 which are spaced apart to accommodate a core back-up plate between them. Attached to plate 37 are two miniature fluid cylinders 38 which serve to grip the core back-up plate firmly between fingers 36 and 37 so that the core plate may be picked up and moved from one position to another by rotating the arm 31.

The tracks 19 along which the secondary shifter plate moves in its transverse shift are mounted on a primary shifter plate 40 which may be shifted along tracks 41 in a direction parallel to the longitudinal axis of the mold by means of hydraulic cylinder 43.

In operation the apparatus functions either in response to the operator's manual controls or preferably the described sequence of operation may be brought about automatically by the proper combination of timers, relays, limit switches, automatic valves, etc., the details of which would be obvious to one skilled in the art and are not shown.

At the start of a casting cycle the apparatus is situated in the relationship shown in FIGURE 1. The horngate is forward with its spout 13 in the mold. A core 16 and core back-up plate 17, which were placed on the core setting mechanism 15 during the previous cycle, are seated in the bell cavity of the mold. Preferably the core setting mechanism 15 is mounted on the horngate shifter plate 11 independently of the horngate. In addition it is desirable to mount the mechanism 15 on air shock absorbers which permit its movement in the longitudinal direction of the mold. This provides protection against breakage of the core and assures that it will be set firmly in place. As the mold is brought up to casting speed, the flyweights 8 of the centrifugal latches 4 are thrown outwardly, and the hook ends 7 lock the core and core back-up plate in position. At this time the molten metal is dumped into the horngate 10, and from the horngate, it flows into the spinning mold 1 where it is evenly distributed over the inside surface of the mold as shown in the drawing.

If desired the horngate shifter plate may be moved back during the pouring operation until it is in the position shown in FIGURES 4 and 5. This makes it possible to distribute the metal impingement over a larger area of the mold in order to prevent overheating of the landing area and the accompanying reduction in mold life. However, if it is not necessary to do this, such as in casting of smaller diameter pipe where the problem is not so great, then a short spout horngate may be used and the horngate shifter plate is unnecessary. The following discussion is based upon the use of a long spout horngate to accomplish impingement spreadout, and accordingly, if this feature is not used and a short spout horngate is substituted, the operation of the machine will be the same, except that the horngate shifter plate will become inactive.

As soon as the pour is complete, the primary shifter

plate 40 moves back to withdraw the horngate spout 13 and core holder 15 from the mold, leaving the core 16 and core ring 17 held in the mold by centrifugal latches 4. In addition, the secondary shifter plate 18 moves to the right until the core ring pick-up means 20 is in alignment with the end of the mold 1. Simultaneously, the fluid cylinder 21 moves the core ring transfer arm 30 forward until the spacing between fingers 36 and 37 is in transverse alignment with the core plate 17. After the primary and secondary shifter plates have moved as described, the apparatus is positioned in the relationship shown in FIGURE 4. It will be noted that there are two core rings in use in the operation of the machine. The first core ring 17 is held in the mold which is still spinning at this time, and the second core ring 17', which was the core ring used during the previous casting cycle, is held on the core ring pick-up magnet 22.

At this time, the core ring transfer arm 30 rotates to the left until the core ring 17' is between fingers 36 and 37 as shown in solid lines. The miniature fluid cylinders 38 are activated and the core ring is firmly held between the end faces of the cylinder rods and finger 36. Fluid cylinder 21 is activated and moves the core ring transfer arm 31 forward, to the first position shown in dash lines, to clear core ring 17' from the face of the pole face 23. Rotor 31 is now rotated to the right until the pick-up arm is in the second position shown in dash lines where the core ring 17' is in longitudinal alignment with and spaced from the horngate spout 13 and the core holder 15. Fluid cylinder 21 is reversed and moves the transfer arm back to the third position shown in dotted lines where the core ring is around the horngate spout. At this point, if a horngate with a short spout is used the core ring will be seated on the core holder. On the other hand, a horngate with long spout, as illustrated, must be shifted forward by means of shifter plate 11, until the core ring is seated on the core holder.

The miniature fluid cylinders are now reversed to release the core ring, the rotor 31 is reversed to return the transfer arm 30 to a vertical position and the fluid cylinder 21 activated to move the transfer mechanism back to its original position. An alternate arrangement wherein the longitudinal movement of the transfer arm is accomplished by two tandem connected fluid cylinders as shown in FIGURES 6 and 7. With this arrangement the piston 122 of cylinder 121 first moves cylinder 123, which is slidably mounted, forward with the transfer mechanism 30. After the core ring 17 has been picked off the pick-up magnet 22, cylinder 123 is activated. Since the piston rod 124 cannot move, the cylinder 123 moves forward and carries with it transfer mechanism 30 to the position desired for placing the core ring 17' on the core holder.

When the above operation is completed nothing further happens until the metal in the mold solidifies, at which time the mold drive motor is de-energized and the mold coasts to a stop. Simultaneously, the primary shifter plate 40 is moved forward until the pole face 23 of the magnet is against the core back-up plate 17 as shown in FIGURE 6. The spring shock absorber 27 provides a positive pressure against the core ring to assure that the raised portion of the pole face enters the hole in the center of the core ring. If an electromagnet is used, it is energized at this time; and this locks the magnet to the core ring and it rotates with the core ring. As the mold coasts to a stop, the centrifugal latches 4 release the core ring which is then held only by the pick-up magnet.

If cores are to be set manually, the core may be placed on the core holder at any time after the core plate 17' has been transferred to the core holder. On the other hand, if it is desired to provide automatic core setting, the last described forward movement of the primary

shifter plate provides an excellent opportunity to accomplish this. Referring now to FIGURE 5, a core 16' is held in position by any suitable means, not shown, so that it is in longitudinal alignment with the horngate spout 13 and core holder 15, and it is longitudinally spaced from the core holder a distance equal to the distance which the primary shifter plate moves when it shifts forward to accomplish pick up of the core ring 17 in the mold. Referring now to FIGURE 6, it is seen that at the same time the pick-up magnet moves forward to pickup the core ring 17, the core holder 15 moves into the core 16'. The core 16' may be a simple device which holds only one core at a time, but permits the operating crew to place it there any time during the cycle. It may also comprise a device which holds several cores at a time and automatically moves another core into place after a core has been picked up by the core holder or it may even be an automatic indexing conveyor which may bring the cores from some other location, for example, the core room.

Turning now to FIGURE 5, the water box 2 is shown moving away from the primary shifter plate 4. The push-out lance, not shown, mounted at the opposite end of the water box is mounted so that when the water box is in casting position it is spaced a predetermined distance from the spigot end of the mold. This distance is greater than the length of the horngate spout so that, as shown in FIGURE 7, extraction of the pipe does not start until the pipe has moved away from the primary shifter plate sufficiently to permit the horngate to be moved into axial alignment with the mold. As soon as the pipe in the mold has made contact with the push-out lance, the secondary shifter plate 18 moves to the left. The core ring 17 is now held on the pick-up magnet 23 and the horngate 10 and the core holder 15 are now in alignment with the mold. The core 16' has been removed from whatever means was used to hold it in the position shown in FIGURES 5 and 6 and it is now in position to be inserted into the mold for casting of the next pipe.

After the previously cast pipe is extracted and transferred out of the path of the water box 2, the water box again moves toward the primary shifter plate to the position shown in FIGURE 1. As it moves into this position the horngate spout 13, core 16' and core ring 17 enter the mold. At this point, the machine is ready to start a new cycle.

The invention is not limited to the specific embodiments set forth in the drawings and description which may be modified in different manners within the scope of the invention as set forth in the appended claims.

We claim:

1. Centrifugal casting apparatus comprising:

- (A) A cylindrical pipe mold rotatably mounted about its longitudinal axis,
- (B) A support mounted adjacent an end of the mold and movable transversely and longitudinally with respect to the longitudinal axis of the mold,
- (C) Shifting means for moving the support from a first transverse position to a second transverse position with respect to the longitudinal axis of the mold,
- (D) A horngate mounted on said support so as to be aligned with the bore of the mold when the said support is in a first transverse position with respect to the longitudinal axis of the mold,
- (E) Core holding means for rotatably holding a core and core ring about the spout of said horngate coaxially with respect to the longitudinal axis of the mold when the support is in the first transverse position with respect to the longitudinal axis of the mold,
- (F) A core ring pick-up means rotatably mounted on said support with its axis parallel to the longitudinal axis of the mold and which coincides with the longitudinal axis of the mold when the support is in the second transverse position with respect to the longitudinal axis of the mold,

(G) Transfer means for transferring a core ring from the core ring pick-up means to the said core holding means.

(H) Latching means for holding a core and core ring securely in the end of the mold while it is rotating, and

(I) Means for moving the support longitudinally with respect to the mold whereby said horngate spout and said core holding means are inserted into and withdrawn from the end of the mold.

2. Apparatus according to claim 1 wherein the core transfer means comprises a reversible rotor, an arm mounted on said rotor, the outer extremity of the arm being provided with spaced apart fingers adapted to receive a core ring therebetween, and means for securing the core ring between the fingers.

3. Apparatus according to claim 2 wherein the reversible rotor is slidably mounted on said support along a line parallel to the axis of the mold and located between the core pick-up means and the horngate, and means for

sliding the rotor from a first position wherein the fingers engage a core ring on the core ring pick-up means when the rotor is rotated in one direction to a second position wherein the core ring is removed from the core ring pick-up means and aligned with the horngate spout when the rotor is rotated in a reverse direction, the core ring being seated on said core holder when the rotor is returned to said first position.

4. An apparatus according to claim 3 wherein the core ring pick-up means comprises an electromagnet mounted on the end of a rotatably mounted shaft.

5. A centrifugal casting apparatus comprising:

- (A) A cylindrical pipe mold rotatably mounted about its longitudinal axis,
- (B) A shifter plate adjacent the bell end of a mold and movable in a direction parallel to the longitudinal axis of the mold,
- (C) A support mounted on said shifter plate and movable transversely of the longitudinal axis of the mold to a first position and a second position,
- (D) A horngate mounted on said support so that its spout is aligned with the end of the mold when the support is in said first transverse position,
- (E) Core holding means for rotatably holding a core and core ring about the horngate spout so that they are co-axial with the mold when the support is in said first transverse position,
- (F) A core ring pick-up means rotatably mounted on said support with its axis co-axial with the longitudinal axis of the mold when the support is in said second transverse position, and
- (G) Transfer means provided for transferring a core ring from the core ring pick-up means to the core holder and being mounted on said support therebetween.

6. Apparatus according to claim 5 wherein the core transfer means comprises a reversible rotor, an arm mounted on said rotor, the outer extremity of the arm being provided with spaced apart fingers adapted to receive a core ring therebetween, and means for securing the core ring between the fingers.

7. Apparatus according to claim 6 wherein the reversible rotor is slidably mounted on said support along a line parallel to the axis of the mold and located between the core pick-up means and the horngate, and means for sliding the rotor from a first position wherein the fingers engage a core ring on the core ring pick-up means when the rotor is rotated in one direction to a second position wherein the core ring is removed from the core ring pick-up means and aligned with the horngate spout when the rotor is rotated in a reverse direction, the core ring being seated on said core holder when the rotor is returned to said first position.

8. An apparatus according to claim 7 wherein the core

ring pick-up means comprises an electromagnet mounted on the end of a rotatably mounted shaft.

9. Apparatus according to claim 5 wherein said horn-gate is mounted on a third shifter plate which is slidably mounted on said second shifter plate in a direction parallel to the longitudinal axis of the mold.
